GEORGE FRANÇOIS JAUBERT, OF PARIS, FRANCE.

ELECTROLYZING APPARATUS FOR THE MANUFACTURE OF OXYGEN AND HYDROGEN.

Application filed April 4, 1922. Serial No. 549,602.

To all whom it may concern:

Be it known that I, GEORGE FRANÇOIS JAUBERT, a citizen of the Swiss Republic, and residing in Paris, France, 155 Boulevard Malesherbes, have invented certain new and useful Improvements in and Relating to Electrolyzing Apparatus for the Manufacture of Oxygen and Hydrogen, of which the following is a complete specification.

10 In the electrolyzing apparatus which are to be used for the manufacture of oxygen and hydrogen with an alkaline electrolyte and electrodes of cast-iron, iron or steel, it has been proposed, very long ago, to separate the anodic and cathodic compartments by means of a metallic diaphragm such as wire-gauze, or perforated sheets of metal. The said apparatus has given no industrial result.

20 I have found that the bad results hereto obtained are due to the fact that with the electrodes of cast-iron, iron or steel, a formation of soluble compounds takes places which are decomposed in the course of the electrolysis and deposit upon the electrodes and stop the apertures of the wire-gauze.

It is consequently absolutely necessary, because of the said stopping, to use a gauze or a net with rather coarse mesh and then 30 the pureness of the gas is questionable in such a degree that the said gas cannot be used for industrial purposes.

I have found that when using for all metallic parts which are dipping in the electrolyte (aqueous solution of alkalies either caustic or carbonated) and directly submitted to the action of the electric current, that is to say for the electrodes and electrode stems, an acid proof metal which cannot be 40 bitten or acted upon in the said conditions, it is then possible to use as a diaphragm, a wire-gauze or a metallic plate finely perforated without the perforations of said diaphragm becoming obstructed.

45 If this said metallic diaphragm is constantly maintained immersed in the liquid, (which is necessary) and if the diameter of each aperture in the diaphragm (wire-gauze, perforated plate) is small enough so that the 50 superficial pressure at the surface of separation of both fluids (liquid, gas or emulsion), which are in the anodic compartment as well as the cathodic one, is stronger than the pressure existing in the said two compartments and constantly tending to provoke

the mixing of both gases, then a complete separating is obtained, and both gases obtained are at a very high degree of pureness.

In the construction of electrodes, and electrode-stems, it is possible to use for instance either sheets or stems of pure nickel or cast-iron or laminated sheets of iron or of steel, which are strongly covered with nickel, preferably with a hot process.

In the drawing is illustrated a practical embodiment of the invention and in which:

Figure 1 is a sectional view of a portion of the apparatus;

Figure 2 is a sectional view at right angles to Figure 1; and,

Figure 3 is a plan view partly in section and broken away.

Referring to the drawing A is a tank having double walls with a filling of sand *a* between them and B the electrolyte. Supported in the tank above the bottom thereof is a frame C preferably of insulating material and having perforations *c* in its bottom and carrying the diaphragms D. E are the electrodes of pure nickel on laminated steel heavily covered with nickel, supported on the bottom of the frame. The electrodes have hollow stems *e* which pass through the top of the frame and strips *e*² to which the 75 electric wires are attached.

For the tank and the other parts of the apparatus which are not under tension, that is to say which are not submitted to the action of the electric current, the use of iron 90 does not offer any drawback. It is of course possible to give any shape to the electrolyzer. The distance between two electrodes is the same as the space between the member *c*² of the frame (15 to 30 mm.), the diaphragm 95 which is moulded or otherwise secured in and transversely of the frame being at a distance of 7.5 to 15 mm. from the electrodes. The substance of which the frame is formed may be for instance gutta-percha, ebonite, cement 100 which may be either pure or mixed with siliceous sand, etc.

The gases which escape from the cells and which are alternately oxygen and hydrogen are gathered at the external part of the apparatus, for instance by means of hollow electrode-stems (such for instance as described in my French patent application filed February 8, 1917) or by any other means. As to the electrolyte, it arrives 110

through the holes in the bottom of the frame and is formed for instance by caustic soda at 15%.

This apparatus offers the following advantages:

The foraminous metallic diaphragm which perfectly withstands the high temperatures (70-85° C.) renders possible the use of a very high strength of current, so that it is possible to make the apparatus with a very little volume.

On the other hand, the use of electrodes and electrode stems of nickel or of metal covered with nickel preserves the purity of the electrolyte and enables the use of a diaphragm with very fine apertures so that the gases produced are very pure, the said purity easily attaining more than 99%.

The diaphragm is preferably of pure nickel (wire-gauze or perforated laminated sheets) or of another metal strongly covered with nickel, though the said condition is not absolutely necessary.

The fineness of the mesh of the wire gauze

sheets or the size of the diameters of the perforations in the foraminous metal sheets is important, the number of openings had, should be between 100 and 120 to a square mesh.

What I claim is:

1. An apparatus for manufacturing oxygen and hydrogen by electrolysis, having nickel electrodes, and nickel diaphragms perforated to form a fine mesh and separating the electrodes.

2. An electrolyzer for manufacturing oxygen and hydrogen comprising a tank containing an electrolyte, nickel electrodes having tubular stems of the same material, a frame supported in the tank and supporting the electrodes and foraminous diaphragms of fine mesh and mounted in the frame and separating the electrodes.

In testimony I have hereunto set my hand at Paris, France, this 24th day of March, 1922.

GEORGE FRANÇOIS JAUBERT.
